CATHODE-RAY TUBE SCANNING CIRCUIT

Richard L. Snyder, Jr., Princeton, N. J., assignor
to Radio Corporation of America, a corporation
of Delaware

Application January 31, 1946, Serial No. 644,524

10 Claims. (Cl. 315—22)

1

This invention relates to cathode ray scanning circuits, and has for its principal object the provision of an improved scanning circuit and method of operation whereby the electron beam of a cathode ray tube is made to scan the target of such a tube in a spiral path once for each pulse applied to the input of the scanning circuit.

In connection with the operation of pulse radar systems and other systems including a cathode ray tube of the storage type, it is desirable (1) to deflect the electron beam of the tube over as long a path as possible in order to obtain maximum resolution of the values stored in the target, (2) to start the scanning cycle at any time a synchronizing pulse is applied to the input of the scanning circuit, (3) to follow the same scanning cycle without deviation each time a synchronizing pulse is applied, (4) to start the scanning cycle within a few microseconds after the synchronizing pulse is received, and (5) to turn the beam on at the beginning of the scanning cycle and off at the end of this cycle in order to avoid fluctuations incident to the operation of the scanning circuit during its return to its normal standby condition.

For achieving these various results, there are provided three separate channels having a common input terminal to which the synchronizing pulses are applied. Two of these channels function to produce in the beam deflection coils of the cathode ray tube currents which are in quadrature, the current of one coil being zero and that of the other being a maximum when the starting pulse occurs so that there are produced in the separate deflecting coils oscillations which are 90° apart and gradually decrease in amplitude. This results in a rotating magnetic field by which the electron beam of the tube is constrained to move in a spiral path. The other of the three channels functions to bias off the electron beam at the end of the scanning cycle and to bias it on the beginning of the scanning cycle.

Important objects of the invention are the provision of an improved scanning system which completes one scanning cycle in response to the application of any single or isolated pulse, the provision of a scanning circuit which initiates scanning of the target without appreciable time delay, and the provision of means whereby the effect of undesired fluctuations on the movement of the beam is avoided.

The invention will be better understood from the following description considered in connection with the accompanying drawing and its scope is indicated by the appended claims.

2

The single figure of the drawing is a wiring diagram of a preferred form of the scanning circuit of the present invention.

This circuit includes an input terminal 20 which is coupled through a capacitor 21 to a "No. 1 channel" which functions to produce in a beam deflecting coil 22 a current which is zero when time equals zero, (2) is coupled through a capacitor 23 to a "No. 2 channel" which functions to produce in a beam deflecting coil 24 a current which is a maximum when time equals zero, and (3) a "No. 3 channel" which functions to bias the beam of the tube 25 on and off at the beginning and end of the scanning cycle.

The No. 2 channel includes a slide back trigger circuit 26 of the multivibrator type, a cathode follower 27 and a pair of triodes 28 which function as a negative resistance. The cathodes of the cathode follower 28 are coupled through a capacitor 29 to one anode of the triodes 28 and are connected to the high voltage side of the beam deflecting coil 24. The low voltage side of the coil 24 is grounded through a lead 31. Connected in shunt to the coil 24 are an adjustable capacitor 32 and any one of the capacitors 33, 34, 35, 36 or 37 which is selected by a movable contact arm 38'. The coil 24 and the capacitors connected in parallel with it form a tuned circuit which is set into oscillation when current conductivity is transferred from the right hand triode to the left hand of the slide back trigger circuit 26, these oscillations being damped by the negative resistance element 28 so that their amplitude decreases in value.

Operating potential is applied from a 300 volt +B lead 38 through a common resistor 39 of 1000 ohms and separate resistors 40 and 41 each of 10,000 ohms to the anodes 42 and 43 of the slide back trigger circuit 26. The bias potential of the grid 44 is determined by the potentials across the resistors 45 of 1.8 megohms and 46 of 120,000 ohms. The cathode 47 is grounded through a 3300 ohm resistor 48. The grid 49 is connected to the cathode 47 through an adjustable 2 megohm resistor 50 and is coupled to the anode 42 through a 3300 microfarad capacitor 51. The output lead 52 of the slideback trigger circuit 26 is coupled through a .01 microfarad capacitor 53 to the common terminal of a 2 megohm resistor 54 and a 10,000 ohm resistor 55 which form the input to the cathode follower 27. The condition of the trigger circuit 26 is stable with current in the triode element 43—49—47 as indicated by the arrow.

The cathode follower 27 has potential applied

to its anodes 56 and 57 from the +B lead 38 through a 25,000 ohm resistor which is adjustable and is bypassed to ground through a 0.1 ohm capacitor 59. The grids 60 and 61 are connected to the resistor 55 and are thus responsive to the potential of the anode 42 of the slide back trigger circuit 26. The cathode 63 is connected through a lead 64 to the high voltage side of the coil 24 and through the 0.1 ohm coupling capacitor 29 to the anode 65 of the negative resistance device 28 as previously indicated. When the slide back multivibrator 26 is stable with current conductivity in its anode 43, the potential of the anode 42 is highly positive and current flows (1) from the lead 38 through the resistor 58, the cathode follower 27, the lead 64, the coil 24 and the lead 31 to ground and (2) from the lead 64 to the capacitor 32 and which ever of the capacitors 33 to 37 is connected in parallel with it. When current conductivity is transferred to the anode 42, the current of the coil is suddenly interrupted and oscillations are set up in the resonant circuit formed by the coil and the capacitors.

The negative resistance device 28 functions to damp the oscillations thus produced so that their amplitude gradually decreases from the first of the oscillations to the last. The device 28 has potential applied from the lead 33 (1) to its anode 65 through a 2200 ohm resistor 65', a 5000 ohm resistor 66 and an 18,000 ohm resistor 67, (2) to its anode 68 through a 12,000 ohm resistor 69, (3) to its grid 70 through an 820,000 ohm resistor 71 and a 56,000 ohm resistor 72, and (4) to its grid 73 through a 1.8 megohm resistor 75 and a 120,000 ohm resistor 74. The grid 73 is coupled through a 1200 microfarad capacitor 76 to an adjustable contact of the resistor 68. The cathode 77 is grounded through a 1500 ohm resistor 78. When the voltage at the high side of the coil 24 is increased, as previously explained, (1) the anode 65 becomes more positive thereby producing an attenuated rise in the voltage of the grid 73, (2) the anode 68 takes more current, (3) the potential of the cathode 77 becomes more positive, (4) the anode 65 takes less current and (5) a more positive potential is applied to the coil 24. This regenerative action functions as a negative resistance across the coil 24. By suitable adjustment of the potentiometer 66, the apparent resistance of the circuit can be made either positive or negative so that the decrement of the resonant circuit formed by the parallel connected coil and capacitors is readily controlled over a wide range.

The "No. 1 channel" includes (1) a buffer amplifier 79 to the grid 80 of which the control pulse of the lead 20 is applied through the 1000 ohm capacitor 21, a 100,000 grid leak resistor 81 being connected between this grid and ground, (2) a cathode follower 82 which is coupled to the anode 83 of the buffer amplifier 79 through a .01 microfarad capacitor 84, and (3) a negative resistance device 85 which is identical with the device 28 and has its anode 86 coupled to the cathodes 87 and 88 of the cathode follower 82 through a 0.1 microfarad capacitor 89. The cathodes 87 and 88 are directly connected to the high voltage side of the beam deflecting coil 22 which is in parallel with an adjustable capacitor 90 and whatever one of the capacitors 91 to 95 are selected by a movable contact arm 96. The coil 22 and the capacitors connected in parallel with it form a resonant circuit in which oscillations 90° out of phase with those of the resonant circuit 24-32 are produced.

The buffer amplifier 79 has +B potential applied to its anodes 100 and 83 through a 1000 ohm common resistor 97 and through individual resistors 98 and 99 each of 10,000 ohms. The cathode 101 is common to the two stages of the amplifier and is grounded through a 2200 ohm resistor 102 which is bypassed by a .01 ohm capacitor 103. The grid 104 of the second amplifier stage 83-104-101 is coupled to the anode 100 through a 3300 microfarad capacitor 105 and is connected to ground through a 100,000 ohm resistor 106 and the parallel circuit formed by the resistor 102 and the capacitor 103. The amplifier 79 functions to apply to the grids 107, 108 and 109 of the cathode follower a pulse of the same polarity as that of the pulse applied to the lead 20. A 3.3 megohm grid leak resistor 110 is connected between the grids 107, 103 and 109 and ground.

From the +B lead, potential is applied to the anodes 111, 112, 113 and 114 of the cathode follower 82 through a 25,000 ohm resistor 115 which is adjustable. When the amplified positive output pulse of the amplifier 79 is applied to the grids 107, 108 and 109 of the cathode follower 82, the rise in the voltage of the cathodes 87 and 88 is so sudden that little or no current flows in the coil 22 and all the energy is stored in the capacitors connected in parallel with this coil. The resulting oscillations are damped by the negative resistance device 85 as explained in connection with the device 28.

It will be noted that the common anode terminals of the units 26, 79 and 82 are bypassed to ground respectively through a 1 microfarad capacitor 116, through a 1 ohm capacitor 117 and through a 1 microfarad capacitor 118 for minimizing the undesired effect of extraneous fluctuations in the potentials at these points.

For damping the oscillations between scanning cycles, the positive pulse produced at the anode 42 of the unit 26 is applied through (1) a filter network including a 100 microfarad capacitor 119 and a 68,000 ohm resistor 120, (2) a 1000 microfarad coupling capacitor 121, and a filter network including a 330,000 ohm resistor 122 and a 3.3 megohm resistor 123 and a .01 microfarad capacitor 124 to the grid 125 of the triode element 114-125-88 which has its cathode 88 connected to the free side of the beam deflecting coil 22. With these connections, the positive wave delivered from the anode 42 is distorted so that it rises to a maximum and gradually decreases. This causes the current of the triode 114-125-88 to rise suddenly damping the oscillations in the resonant circuit formed by the coil 22 and its parallel-connected capacitors. Thereafter this current decreases too slowly to shock the resonant circuit into oscillation and assumes a zero value before the next timing pulse is applied to the input lead 20.

The capacitors 93 and 32 may each have a maximum capacity of 320 microfarads. The capacities of the capacitors 33 to 37 and 91 to 95 of course are fixed by the constants of the deflecting coils 22 and 24 and the frequency at which the target of the cathode ray tube is to be scanned.

From what has been said, it is apparent that the two resonant circuits (1) are tuned to the same frequency, (2) are damped at the same rate, and (3) function together to produce a rotating deflecting magnetic field which gradually decreases in amplitude and causes the electron beam to scan the target in a spiral path,

Otherwise stated, the positive timing pulse applied to the lead 20 always occurs with the current in the coil 22 at its zero value and that in the coil 24 at its maximum value so that current begins to be delivered to the coil 22 from its parallel-connected capacitors and current is delivered from the coil 24 to its parallel-connected capacitors, thus producing in the two tuned circuits oscillations which have the same frequency and differ in phase by 90°.

At the end of each scanning cycle, the electron beam is biased off by means of the "No. 3 channel" which includes (1) a slide back trigger circuit 126 similar to the trigger circuit 26 of the "No. 2 channel" and (2) a double rectifier unit 127. The various details of the trigger circuit 126 are apparent from what has been said in connection with the similar trigger circuit 26. In each case, the trigger circuit is stable only with current conductivity in the right hand anode and is transferred temporarily to the left hand anode in response to application of a positive pulse to the lead 20. After a time interval predetermined by adjustment of the grid resistor 50 or 128, current conductivity automatically returns to the right hand anode. The unit 126 is adjusted to return current conductivity to the right hand anode slightly in advance of the return of conductivity to the anode 43 so that the beam is biased off before any extraneous disturbances occur in the deflecting circuits. The beam is biased on in response to a positive pulse applied to a .01 ohm coupling capacitor 129 and is biased off in response to a negative pulse applied to this coupling capacitor.

These beam biasing pulses are applied (1) through a .01 microfarad capacitor 130, a 560,000 ohm resistor 131 and a .01 microfarad coupling capacitor 132 to the beam control grid 133 of the cathode ray tube 25, and (2) through a 560,000 ohm resistor 134 to the cathode ray tube cathode 135 which is bypassed to ground by a 0.1 microfarad capacitor 136.

The purpose of the double rectifier 137-138 and 139-140 is to prevent overshooting when the beam is turned on and to provide a constant bias potential for the beam during the scanning cycle. This bias potential is provided by a network which includes the resistor 134, a 0.1 microfarad capacitor 141 connected between the upper end of the resistor 134 and the anode 137 and a 1 meg-ohm resistor 142 having an adjustable contact which is connected to the cathode 140 and is also connected through a 0.1 microfarad capacitor 143 to the cathode 135 of the cathode ray tube 25 which is bypassed to ground by capacitor 136. When a negative pulse is applied through the coupling capacitor 129, the cathode 138 pulls the anode 137 negative thus charging the capacitor 141 and establishing a negative bias voltage across the resistor 142. If the beam tends to overshoot, the potential across the resistor 131 increases, the diode 139-140 draws some current through a 1 megohm resistor 144 and the swing of the beam is retarded or stopped. The distributed capacity of the system is sufficient to round off any sudden changes which might otherwise shock into oscillation the sensitive amplifier system to which the output of the cathode ray storage device is connected.

What the invention provides is a scanning system which responds to a single positive pulse to execute only one scanning cycle wherein the beam moves over the target in a spiral path. While the invention is disclosed as applied to a

cathode ray of the storage type, it is obviously applicable to other types of apparatus which utilize a constant frequency rotating electrical field of gradually diminishing amplitude.

5 I claim as my invention:

1. The combination of a cathode ray tube having a cathode and a ray control grid and a pair of ray deflecting coils, a pair of tuned circuits each including a different one of said coils, means responsive to an electrical pulse for producing oscillations in the first of said tuned circuits, means responsive to said electrical pulse producing in the second of said tuned circuits oscillations which are in quadrature with the oscillations of said first tuned circuit, and means responsive to said electrical pulse for biasing off the ray of said tube at the end of a predetermined number of said oscillations.
2. The combination of a cathode ray tube having a cathode and a ray control grid and a pair of ray deflecting coils, a pair of tuned circuits each including a different one of said coils, means responsive to an electrical pulse for producing oscillations in the first of said tuned circuits, means responsive to said electrical pulse for producing in the second of said tuned circuits oscillations which are in quadrature with the oscillations of said first tuned circuit, and a network interconnecting said means for terminating the oscillations in one of said tuned circuits at a predetermined time after the occurrence of said electrical pulse.
3. The combination of a cathode ray device wherein the intensity of a cathode ray is controlled by a grid and the position of said ray is controlled by vertical and horizontal ray deflecting coils, two groups of capacitors, simultaneously operated means for selectively connecting the capacitors of one of said groups in parallel with one of said coils to form a first tuned circuit and the capacitors of the second of said groups in parallel with the other of said coils to form a second tuned circuit, means for applying an electrical pulse, means responsive to said pulse for shock exciting said tuned circuits to produce in said coils currents which are in quadrature, and means for attenuating said currents at the same rate.
4. The combination of a cathode ray device wherein the intensity of a cathode ray is controlled by a grid and the position of said ray is controlled by vertical and horizontal ray deflecting coils, two groups of capacitors, simultaneously operated means for selectively connecting the capacitors of one of said groups in parallel with one of said coils to form a first tuned circuit and the capacitors of the second of said groups in parallel with the other of said coils to form a second tuned circuit, means for applying an electrical pulse, means responsive to said pulse for shock exciting said tuned circuits to produce in said coils currents which are in quadrature, means for attenuating said currents at the same rate, and means responsive to said pulse for biasing on said ray only during the flow of said currents.
5. The combination of a pair of coils arranged to produce a rotating magnetic field in response to currents in quadrature with one another, first and second capacitance means each arranged to be connected across a different one of said coils to form first and second tuned circuits, means for applying an electrical pulse, and means responsive to said pulse for shock exciting said

tuned circuits to produce in them currents which are in quadrature with one another.

6. The combination of a pair of coils arranged to produce a rotating magnetic field in response to currents in quadrature with one another, first and second capacitance means each arranged to be connected across a different one of said coils to form first and second tuned circuits, means for applying an electrical pulse, means responsive to said pulse for shock exciting said tuned circuits to produce in them currents which are in quadrature with one another, and means for attenuating said currents at the same rate.

7. The combination of a pair of coils arranged to produce a rotating magnetic field in response to currents in quadrature with one another, first and second capacitance means each arranged to be connected across a different one of said coils to form first and second tuned circuits, means for applying an electrical pulse, means responsive to said pulse for shock exciting said tuned circuits to produce in them currents which are in quadrature with one another, and simultaneously operated means for adjusting the value of the capacitances connected across said coils so that said circuits are always tuned to the same frequency.

8. The combination of a pair of coils arranged to produce a rotating magnetic field in response to currents in quadrature with one another, first and second capacitance means each arranged to be connected across a different one of said coils to form first and second tuned circuits, means for applying an electrical pulse, first and second cathode followers each having its cathode connected to the free side of a different one of said tuned circuits, a trigger circuit responsive to said pulse for deenergizing said first cathode follower during a predetermined time interval, and amplifying means responsive to said pulse for energizing said second cathode follower during said time interval.

9. The combination of a pair of coils arranged to produce a rotating magnetic field in response to currents in quadrature with one another, first and second capacitance means each arranged to be connected across a different one of said coils to form first and second tuned circuits, means for applying an electrical pulse, first and second

cathode followers each having its cathode connected to the free side of a different one of said tuned circuits, a trigger circuit responsive to said pulse for deenergizing said first cathode follower during a predetermined time interval, amplifying means responsive to said pulse for energizing said second cathode follower during said time interval, and means for attenuating the currents of said coils at the same rate.

10. The combination of a pair of coils arranged to produce a rotating magnetic field in response to currents in quadrature with one another, first and second capacitance means each arranged to be connected across a different one of said coils to form first and second tuned circuits, means for applying an electrical pulse, first and second cathode followers each having its cathode connected to the free side of a different one of said tuned circuits, a trigger circuit responsive to said pulse for deenergizing said first cathode follower during a predetermined time interval, amplifying means responsive to said pulse for energizing said second cathode follower during said time interval, and means connected between the second of said cathode followers and said trigger circuit for attenuating oscillations tending to occur after the expiration of said time interval.
